SWITCH

Calvin J. Werner, Dayton, Ohio, assignor to
General Motors Corporation, Detroit, Mich., a
corporation of Delaware

Application October 21, 1936, Serial No. 106,723

20 Claims. (Cl. 200—124)

This invention relates to a thermal responsive switch, and more particularly to such a switch adapted to protect an energy translating device from damage due to overheating.

5 An object of this invention is to provide a switch for protecting an energy translating device from overheating, which switch can be easily and cheaply manufactured and which cannot have the purpose thereof defeated by the user by 10 securing the actuating member in some fixed position. This object is accomplished by providing a switch structure comprising a small number of inexpensive parts, including a thermal responsive latch, that are easy to assemble 15 and by so constructing and arranging the parts that the switch actuating member holds the switch contacts apart while force is applied thereto to actuate the contacts, whereupon the contacts engage upon release of the force applied 20 to the actuating member and whereupon one of the contact members is free of the actuating member upon such release of the pressure applied thereto, so that when the thermal responsive latch releases the said one contact member, the 25 contacts are disengaged irrespective of the position of the actuating member.

Another object of this invention is to provide a thermal responsive switch for protecting an energy translating device, which switch is adapted 30 to receive heat from the energy translating device by virtue of being mounted in heat receiving relation therewith and which is adapted to be provided with means adaptable to the energy translating device and the protection desired for 35 additionally influencing the operation of the switch. This object is accomplished by providing a thermal responsive locking structure that is adapted to have a heating element such as a resistance wire associated therewith and/or a 40 heat conducting element for conducting heat from a part of the energy translating device to the thermal responsive locking structure.

Further objects and advantages of the present invention will be apparent from the following description, reference being had to the accompanying drawings wherein a preferred embodiment of the present invention is clearly shown.

In the drawings:

Fig. 1 is a fragmentary view of a dynamo electric machine equipped with one form of thermal protective device embodying the present invention, said device being broken away to show the interior thereof. The heater element has been omitted for the sake of clearness.

55 Figs. 2, 3 and 4 are views of the thermal pro-

tective device minus its heater element, with parts thereof shown in different positions of operation. These views show the device with the cover removed and looking in the direction of arrow 2 of Fig. 1. Figs. 2, 3 and 4 show a form of the 5 invention different in some details from that shown in Fig. 1.

Fig. 5 is a view taken in the direction of arrow 5 of Fig. 4 inverted, however, and with the heater element attached.

Fig. 6 is a view taken in the direction of the arrow 6 of Fig. 5.

Fig. 7 is a sectional view on the line 7—7 of Fig. 5.

Fig. 8 is a sectional view taken on line 8—8 15 of Fig. 1 and turned through an angle of 90°.

Figs. 9 and 10 are perspective views of a modified form of switch embodying the present invention and indicate one operating position of the switch parts as viewed from substantially opposite sides of the switch.

Figs. 11 and 12 are also perspective views of the switch shown in Figs. 9 and 10 and indicate different operating positions of the switch from substantially opposite sides thereof.

Fig. 13 is an enlarged sectional view of a part 25 of the switch structure.

With particular reference to Figs. 1 to 8 inclusive, similar reference numerals refer to similar parts. A switch 10 has a housing 12 that is preferably made of insulating material, such as molded "Bakelite" or similar material, which housing is provided with a cover 14, also preferably made of insulating material. The housing 12 has slots 16 and 18 in one end thereof in which resilient switch arms 20 and 22 respectively are anchored. Connector lugs 24 and 26 that are preferably integral with the switch arms 20 and 22 respectively, extend outwardly from the housing 12 for making electrical connections to the switch arms. The switch arms 20 and 22 extend into the housing 12, out of contact with the walls thereof, and have contacts 28 and 30 respectively mounted thereon in alignment for engagement. The switch arms 20 and 22 are normally biased to 30 positions, substantially as indicated in Fig. 2, such that the contacts 28 and 30 are out of engagement. The switch arm 20 is preferably longer than the switch arm 22, so that it extends beyond the end of the switch arm 22; the switch arm 20 having a pawl 32 provided thereon, preferably by bending the end of the arm 20 in substantially the form of a hook. The switch arms 20 and 22 have lugs 34 and 36 respectively on the 35 sides thereof which are preferably intermediate

the ends of the switch arms. Resilient reinforcing leaf springs 38 and 40, preferably made of spring steel and that are substantially the same shape as the switch arms 20 and 22 respectively, but somewhat shorter than the switch arms, extend along one side of those portions of the switch arms that are subject to flexure, and are anchored in the slots 16 and 18 in the end of the housing. These leaf springs 38 and 40 have lugs 41 and 43 thereon that correspond to and are in alignment with the lugs 34 and 36 on the switch arms. The switch arms 20 and 22 and the reinforcing strips 38 and 40 each have lugs such as those indicated at 42 and 45 thereon which fit into cooperating recesses 44 and 47 respectively in the housing 12 to aid in the anchoring of the switch arms and reinforcing springs.

A tubular stud 46 extends through the housing 12 and fits an opening 48 in one wall of the housing. A ratchet wheel 50 is rotatably mounted on the stud 46, and is normally held stationary with respect to the stud by a layer of solder or other similar bonding material at 52 intermediate the stud and ratchet wheel, which fusible material fuses or melts at a temperature abnormal to the energy translating device with which the switch is used. The stud 46 and ratchet wheel 50 are located in position for latching engagement with the pawl 32 when the switch arm 20 is flexed toward the switch arm 22. Figs. 1 to 7 inclusive indicate the preferable form of switch for use when it is desirable to have the switch responsive to current flow through a winding of the energy transferring device with which it is used. A resistance wire heater element 54 has one end anchored in an opening 56 at one end of the stud, and extends substantially axially through the hollow stud. This heater element 54 is connected into the circuit of the energy translating device by a connecting lead 57 which is electrically connected to the end of the stud 46 and preferably soldered thereto, as at 58, and is also connected to the connector lug 24 by soldering, as at 60. In the Figs. 1 to 4 the heater element 54 has not been included for the purpose of simplifying the drawings. This heater, however, is shown in Figs. 5, 6 and 7.

In a modified form of the switch, such as that shown in Figs. 1 and 8, where it is desired to have the switch responsive to the temperature of the windings of the energy translating device for which it is used and to omit the heater element 54, an angular plate 62 of heat-conducting material, such as copper, preferably has the stud 46 extruded from one side thereof and integral therewith to provide high heat conductivity from the plate to the stud. This plate 62 extends along one side of the housing and is preferably mounted against the winding of the energy translating device, substantially as indicated in Fig. 1, for conducting heat from the winding to the stud. In either case, the stud preferably extends through an opening 68 in the cover 14 and is riveted over, as at 66, to hold one end of the cover 14 in place.

A manually operable actuating member 70 extends through an opening 72 in the housing 12. This actuating member 70 has openings 74 and 76 therein, into which the lugs 34 and 36 respectively, extend. In order to have trip-free operation of the switch, the opening 74 is preferably larger than the opening 76. That is, these openings are preferably of such size and so spaced that when force is applied to the actuating member 70 which moves that actuating

member and the switch arm 20 to the left, as viewed in Figs. 2, 3 and 4 the contacts 28 and 30 are held apart by virtue of the spacing of the surfaces 73 and 75 of the openings 74 and 76 respectively, and the normal bias of the switch arms 20 and 22 and substantially as illustrated in Fig. 3. Further, when the pawl 32 engages the ratchet 50 to hold the switch arm 20 in a flexed position, the switch arm 22 biases the actuating member to the right as viewed in Fig. 3, so that when the pressure on the actuating member 70 is released, the bias of the switch arm 22 against the surface 75 effects movement of the actuating member in the direction of the bias, which movement effects engagement of the contacts. This movement of the actuating member that occurs responsive to the bias of the switch arm 22 to effect engagement of the contacts provides a space between the surface 73 of the opening 74 and the lug 34, substantially as indicated in Fig. 4. Hence, when the fusible material that holds the ratchet wheel 50 stationary with respect to the stud 46 melts, and the contacts 28 and 30 are engaged, the switch arm 20 is free of the actuating member 70, so that the bias of the switch arm 22 turns the ratchet wheel 50 on the stud 46 to release the pawl 32 from the ratchet wheel 50 and effect disengagement of the contacts 28 and 30.

As previously explained, the stud 46 is riveted at 66 to hold one end of the lid 14 in place. The other end of the lid is held by a rivet or other suitable fastening means 78 that extends through an opening 80 in the housing 12 and through an opening 82 in the lid 14 and which is riveted at 83.

As illustrated in Fig. 1, the switch is adapted to be mounted in heat receiving relation to an energy translating device 84 having a frame or housing 85 and an end head 86. The switch 10 is secured or tied therein in such a position that the heat conducting plate 62 is against the end turns 87 of the windings of the energy translating device and the actuating member 70 extends outwardly through an opening 88 in the end head. The actuating member is thus accessible from the outside of the energy translating device for manual resetting of the switch to contact closed position. A bezel 90 is preferably provided around the opening 88.

It is understood that when desirable for use with a particular form or type of energy translating device, the heat conducting plate 62 can be used in conjunction with a heating element such as 54. However, a switch incorporating the heating element 54 is preferably mounted within the housing of an energy translating device in such a position that it is influenced by heat from the energy translating device.

With particular reference to Figs. 9 to 13 inclusive, similar reference numerals refer to similar parts. In this form of switch, a base 100 of any suitable insulation material, has switch arms 102 and 104 secured thereto by rivets 106 and 108 respectively, or other suitable fastening means. The ends of the switch arms 102 and 104 that are secured to the base 100 are preferably separated, and the switch arms preferably extend angularly toward each other so that the free ends thereof are near one another. An angular contact member 110 having a contact portion 112 that extends toward the switch arm 104 is secured to an end portion 114 of the switch arm 102 by a rivet 116 or other suitable fastening means. The portion 114 of the switch arm 78

102 is angularly disposed with respect to the rest of the switch arm. A stud 118 is secured to an angularly disposed end 120 of the switch arm 104 by riveting the end of the stud at 122. A shoulder 124 on the stud 118 engages the side of the portion 120 of the switch arm 104 opposite the riveted portion 122 of the stud. The stud 118 is preferably hollow, and has a contact support 126 secured in an opening 128 in the end portion 130 of the stud opposite the riveted end thereof, so that the contact support 126 extends through the hollow stud substantially coaxially therewith and projects from the end thereof. This contact support 126 is made of resistance material and provides a heating element when it is desired to have the stud heated in accordance with the current flow through the switch. If such heating is not desired, the stud is made of a material of higher conductivity. A contact 132, preferably having a substantially circular contact surface is secured to the projecting end of the contact support 126 in alignment for engagement with the contact 112. The switch arms 102 and 104 are preferably inherently resilient and are so biased that the contacts 112 and 132 are normally out of engagement.

A ratchet wheel 134 is rotatably mounted on the outer surface of the stud 118, and is normally bonded to the stud and held in a fixed position relative thereto by a layer of fusible material 136 that is preferably intermediate to the stud 118 and the ratchet wheel 134. This fusible material, such as solder, melts at a temperature abnormal for the device with which the switch is used, and which the switch protects. An arm 138 which is preferably integral with the switch arm 104 is bent at the end thereof to provide a pawl 140 which engages the ratchet wheel 134 to hold the switch arm 104 in a flexed position such that the contacts 112 and 132 are engaged. The arm 138 is preferably integral with the switch 104 so that the switch arm 104 and the arm 138 cannot turn relative to each other to effect disengagement of the pawl from the ratchet wheel due to causes such as vibration. When the fusible material is melted by excessive heat, the normal bias of the switch arm 104 effects a turning movement of the ratchet wheel 134 on the stud 118 and a consequent release of the ratchet wheel from the pawl 140, whereupon the switch arms assume positions substantially as indicated in Figs. 9 and 10.

A manually operable actuating member 142 is slidably mounted adjacent the switch arms 102 and 104 in a suitable support such as that indicated at 144 which may be the end frame of a dynamo electric machine. The actuating member 142 is movable toward or away from the switch arms 102 and 104, and has a flange portion 146 which acts as a stop to prevent the actuating member from coming out of the support 144 and is sufficiently large to engage both of the switch arms 102 and 104.

Upon movement of the actuating member 142 toward the switch arms 102 and 104, and the continued movement thereof in that direction, the flange 146 engages the arms 102 and 104 to effect movement of both of the arms against the normal bias thereof. The arm 104 is thus moved to such a position that the pawl 140 engages the ratchet wheel 134 to prevent return movement of the switch arm 104. By virtue of the differences in distances between the contacts 112 and 132 and the parts of the arms 102 and 104 respectively which engage the flange

146, the contacts 112 and 132 are held apart as long as sufficient force is applied to the actuating member 142 to overcome the bias of the arm 102. That is, by movement of the actuating member 142 which effects engagement of the ratchet wheel 134 with the pawl 140, the switch arm 102 moves to a position such as that indicated in solid lines in Fig. 11. Upon release of the pressure upon the actuating member 142, so that the contact arm 102 moves the actuating member in the direction of the bias of that arm, the arm 102 and actuating member 142 return to a position such as that indicated by the dot-and-dash lines in Fig. 11; whereupon the contacts engage as indicated in Fig. 12. When the contacts are in engagement, there is sufficient space between the switch arm 104 and the flange 146 that the arm 104 is free of the actuating member and disengagement of the contacts will follow a release of the ratchet wheel from the pawl.

Both of the forms of the switches disclosed herein are similar in principle and operation; and both are adapted to be mounted in heat receiving relation to an energy translating device, such as a dynamo electric machine, so that the fusible material that normally holds the ratchet wheel in place is melted by excessive heat from the energy translating device. That is, each of the switches is adapted to be mounted, for instance, within the end frame of the motor, so that the actuating member extends thru the end frame. Also, when desirable, both of the switches are adapted, as described, to include a heating element which is connected in the circuit of the energy transmitting device to provide heat in addition to that of the energy translating device and corresponding to the current flow in a circuit of the energy translating device.

Both of the forms of the invention disclosed herein are trip-free. That is, the only part of the switch that is readily accessible is the actuating member; and the purpose or protective feature of the switch cannot be defeated by tying or securing the actuating member in any position. Sufficient force applied to the actuating member of either of the forms holds the contacts apart. When sufficient force is applied to the actuating member, one switch arm, in each case, is locked in a substantially fixed position by engagement of the pawl and ratchet wheel while the contacts are held apart. After the engagement of the pawl and ratchet wheel, the release of the force applied to the actuating member permits a return movement of the actuating member and one of the switch arms by virtue of the bias of that latter mentioned switch arm until the contacts engage. The portion of the actuating member which engages the locked switch arm having moved away from the locked switch arm during the return movement effected by the bias of the other switch arm, a clearance is provided between the locked switch arm and the actuating member which is sufficient to permit separation of the contacts upon release of the pawl from the ratchet wheel.

It is thus clear that securing the actuating member in some positions will hold the contacts apart; while securing the actuating member in a position in which the contacts are engaged leaves the locked switch arm free to move with respect to the actuating member.

While the embodiment of the present invention as herein disclosed, constitutes a preferred form, it is to be understood that other forms might be

adopted, all coming within the scope of the claims which follow.

What is claimed is as follows:

1. A thermal responsive switch for the protection of an energy translating device comprising in combination, a base; a pair of switch arms each having one end anchored to the base and each having a contact thereon in alignment for engagement with the contact on the other arm, said arms being normally biased to positions such that the contacts are disengaged; a ratchet wheel; means rotatably supporting the ratchet wheel, said ratchet wheel being normally held stationary by a material that is fusible at an abnormal temperature of the energy translating device; means engaging the ratchet wheel to hold the arms in contact engaged position against the normal biasing force of the arms; a manually operable actuating member for moving one of the arms to contact engaged position, said actuating member holding the arms apart so that the contacts cannot engage while manual force is applied thereto.
2. A thermal responsive switch for the protection of an energy translating device comprising, in combination, a base; a pair of switch arms each having one end anchored to the base and each having a contact thereon in alignment for engagement with the contact on the other arm, said arms being normally biased to positions such that the contacts are disengaged; a locking element; means movably supporting the locking element, said locking element being normally held stationary by a material that is fusible at an abnormal temperature of the energy translating device; means engaging the locking element and adapted to hold the arms in contact engaged position against the normal biasing force of the arms; a manually operable actuating member for effecting engagement of the last mentioned means with the locking element, said actuating member holding the arms apart during movement toward engagement of said locking element with the last mentioned means and until said actuating element is effectively released, one of said arms being free to move from the contact engaged position upon release of said means from the locking element even when the actuating element is held in any position which permits engagement of the contacts.
3. A thermal responsive switch for the protection of an energy translating device comprising, in combination, a base; a pair of switch arms each having one end anchored to the base and each having a contact thereon in alignment for engagement with the contact on the other arm, said arms being normally biased to positions such that the contacts are disengaged; a stud in heat receiving relation with the energy translating device, a ratchet wheel mounted on said stud and adapted to rotate with respect thereto, said ratchet wheel being normally prevented from rotation with respect to the stud by a layer of material intermediate the stud and ratchet wheel that is fusible at an abnormal temperature; a heating element comprising a resistance wire for imparting heat to the stud in addition to that received from the energy translating device, by virtue of being in heat receiving relation therewith, a pawl adapted to engage the ratchet wheel to hold one of the arms against movement in the direction of the normal bias thereof; a manually operable actuating member for moving the said one of the arms to effect engagement of the pawl and ratchet wheel, said actuating member holding the arms apart while force is applied thereto sufficient to overcome the bias of one or both of said arms, said contacts engaging upon release of the actuating member, and said contacts breaking upon fusing of said material and the resulting release of said one of the arms regardless of the position of the actuating member within the limits of movement thereof which permit engagement of the contacts.
4. A thermal responsive switch for the protection of an energy translating device comprising, in combination, a base; a pair of switch arms each having one end anchored to the base and each having a contact thereon in alignment for engagement with the contact on the other arm, said arms being normally biased to positions such that the contacts are disengaged; a stud in heat receiving relation with the energy translating device, a ratchet wheel mounted on said stud and adapted to rotate with respect thereto, said ratchet wheel being normally prevented from rotation with respect to the stud by a layer of material intermediate the stud and ratchet wheel that is fusible at an abnormal temperature; means physically connected to the stud and adapted to conduct heat directly to the stud in addition to the ambient heat from the energy translating device; a pawl adapted to engage the ratchet wheel to hold one of the arms against movement in the direction of the normal bias thereof; a manually operable actuating member for moving the said one of the arms to effect engagement of the pawl and ratchet wheel, said actuating member holding the arms apart while force is applied thereto sufficient to overcome the bias of one or both of said arms, said contacts engaging upon release of the actuating member, and said contacts breaking upon fusing of said material and the resulting release of said one of the arms regardless of the position of the actuating member within the limits of movement thereof which permit engagement of the contacts.
5. A thermal responsive switch for the protection of an energy translating device comprising, in combination, a base; a pair of switch arms each having one end anchored to the base and each having a contact thereon in alignment for engagement with the contact on the other arm, said arms being normally biased to positions such that the contacts are disengaged; a stud in heat receiving relation with the energy translating device, a ratchet wheel mounted on said stud and adapted to rotate with respect thereto, said ratchet wheel being normally prevented from rotation with respect to the stud by a layer of material intermediate the stud and ratchet wheel that is fusible at an abnormal temperature; a heating element comprising a resistance wire for imparting heat to the stud in addition to that received from the energy translating device, by virtue of being in heat receiving relation therewith, a pawl adapted to engage the ratchet wheel to hold one of the arms against movement in the direction of the normal bias thereof; a manually operable actuating member for moving the said one of the arms to effect engagement of the pawl and ratchet wheel, said actuating member holding the arms apart while force is applied thereto sufficient to overcome the bias of one or both of said arms, said contacts engaging upon release of the actuating member, and said contacts breaking upon fusing of said material and the resulting release of said one of the arms regardless of the position of the actuating member within the limits of movement thereof which permit engagement of the contacts.
6. A thermal responsive switch for the protec-

tion of an energy translating device comprising, in combination, a base; a pair of switch arms each having one end anchored to the base and each having a contact thereon in alignment for engagement with the contact on the other arm, said arms being normally biased to positions such that the contacts are disengaged; a stud secured to the base; a locking element movably mounted on the stud and normally held in one position by a layer of fusible material intermediate the stud and locking element; one of said arms having a pawl thereon adapted to engage the locking element to hold the arm against movement in the direction of the biasing force of the arm; a manually operable actuating member for effecting engagement of the pawl and locking element to hold the contacts in engaged position, said actuating member engaging both of the arms to hold them apart during movement in the direction effecting engagement of the pawl and locking element; the other of said arms being biased to effect engagement of the contacts upon release of the actuating member, the said one of said arms being free of the actuating member to move upon release of the pawl when the contacts are engaged.

7. A thermal responsive switch for the protection of an energy translating device comprising in combination, a base; a first switch arm anchored at one end and having a contact mounted near the other end thereof; a second switch arm anchored at one end and having a contact mounted near the other end thereof, said contacts being in alignment for engagement and said arms being normally biased to positions such that the contacts are out of engagement; a stud; a ratchet wheel rotatably mounted on the stud and normally bonded to the stud by a layer of fusible material; means engaging the ratchet wheel to hold the first switch arm against the normal bias thereof, the second switch arm being biased to effect engagement of the contacts when said means engages the ratchet; a manually operable actuating member adapted to engage both of the arms and to effect engagement of said means with the ratchet wheel, said actuating member preventing engagement of the contacts during movement thereof in one direction and said first arm being free of the actuating member upon engagement of the contacts.

8. A thermal responsive switch for the protection of an energy translating device comprising in combination, a base; a first switch arm anchored at one end and having a contact mounted near the other end thereof; a second switch arm anchored at one end and having a contact mounted near the other end thereof, said contacts being in alignment for engagement and said arms being normally biased to positions such that the contacts are out of engagement; a stud secured to the base; a ratchet wheel rotatably mounted on the stud and normally bonded to the stud by a layer of fusible material; a pawl on the end of the first arm adapted to engage the ratchet wheel to hold the first switch arm against the normal bias thereof; the second switch arm being biased to effect engagement of the contacts when the pawl engages the ratchet wheel; a manually operable actuating member adapted to move the first arm to a position of engagement of the pawl with the ratchet, said actuating member engaging the second arm during movement of the first arm toward engagement of the pawl with the ratchet

to hold said arms apart, said second arm being biased to effect engagement of the contacts upon release of the actuating member, said first arm being free of the actuating member when the contacts are engaged.

9. A thermal responsive switch for protecting an energy translating device from damage due to excessive heat comprising, in combination, a base; a first switch arm anchored at one end and having a contact mounted at the other end thereof; a second switch arm anchored at one end and having a contact mounted at the other end thereof in alignment for engagement with the contact on the first arm, said arms being normally biased to positions such that the contacts are out of engagement; a stud secured to one of the arms; a ratchet wheel rotatably mounted on the stud and normally bonded to the stud by a layer of material that is fusible at an excessive temperature of the device; means engaging the ratchet wheel to hold the said one switch arm against the normal bias thereof and in a position such that said contacts are biased into engagement; a manually operable actuating member adapted to effect engagement of the ratchet with said means, said actuating member engaging both of the arms to hold said contacts apart while force is exerted upon the actuating member, one of said arms being free of the actuating member when the contacts are engaged.

10. A thermal responsive switch for protecting an energy translating device from damage due to excessive heat comprising, in combination, a base; a first switch arm anchored at one end and having a contact mounted at the other end thereof; a second switch arm anchored at one end and having a contact mounted at the other end thereof in alignment for engagement with the contact on the first arm, said arms being normally biased to positions such that the contacts are out of engagement; a stud secured to the first arm; a ratchet wheel rotatably mounted on the stud and normally bonded in a fixed position by a layer of material that is fusible at an excessive temperature of the device; a pawl adjacent the first arm for engaging the ratchet to hold the first arm against the normal bias thereof and in a position that the second arm biases the contacts into engagement; a manually operable actuating member adapted to effect engagement of the ratchet with said pawl, said arms and actuating member being so constructed and arranged that the contacts are held apart by force exerted upon the actuating member, said first arm being free to move with respect to the actuating member to effect disengagement of the contacts when the said material fuses at an excessive temperature.

11. In a thermal responsive switch, a subassembly comprising, in combination, a resilient switch arm biased in one direction, a ratchet device secured to the switch arm, an arm integral with the switch arm and having a pawl thereon adapted to engage the ratchet device to hold the switch arm against the normal bias thereof.

12. In a thermal responsive switch, a subassembly comprising, in combination, a switch arm having a movable portion normally biased in one direction and a substantially stationary portion, a stud secured to the movable portion of the switch arm, a ratchet mounted on the stud and adapted to rotate with respect thereto, said ratchet being normally prevented from

rotation with respect to the stud by a layer of material intermediate the stud and ratchet that is fusible at abnormal temperature, an arm integral with the substantially stationary portion 5 of the switch arm and having a pawl thereon adapted to engage the ratchet to hold the switch arm against the normal bias thereof.

13. In a thermally operated switch, a pair of resilient contact arms normally biased to open 10 circuit position, a thermally responsive ratchet mounted on one of said arms and adapted to latch the other arm thereto so that the latched arm forms a closed circuit, said thermally responsive ratchet upon obtaining a predetermined temperature 15 releasing the arms so that they may assume an open circuit position.

14. In a thermally operated switch, a pair of resilient contact arms biased to open circuit position, a thermally responsive ratchet carried by 20 one of said arms, latching means adapted to engage the ratchet so that the contact arms are held in closed circuit position, said ratchet upon obtaining a predetermined temperature disengaging from said means and releasing the arms 25 so that the arms assume an open circuit position.

15. In a thermally operated switch, a pair of resilient contact arms biased to open circuit position, a thermally responsive ratchet carried by 30 one of said arms, latching means adapted to engage the ratchet so that the contact arms are held in closed circuit position, said ratchet upon obtaining a predetermined temperature disengaging from said means and releasing the arms 35 so that the arms assume an open circuit position, and means for resetting the arms in closed circuit position after release.

16. In a thermal responsive switch, a spring terminal member, and a spring contact member, 40 said members being normally biased to open circuit position, thermal means carried by the terminal member including a portion adapted to engage the contact member and to latch the contact member and the terminal member in closed circuit position, said thermal means being adapted 45 to release said members so that they may assume an open circuit position upon the attainment of a predetermined temperature, and an operating member for resetting said contact

member and said terminal member in closed circuit position, said operating member being adapted to open circuit the contact member and the terminal member at will when said members are in latched relation. 5

17. In a thermally operated switch, a pair of resilient contact arms normally biased to open circuit position, thermally responsive means carried by one of said arms and adapted to latch the other arm thereto so that the biased arms 10 form a closed circuit, said means upon obtaining a predetermined temperature releasing the arms so that they may assume open circuit position.

18. A circuit breaker comprising two cooperating contact blades normally biased to circuit 15 open position; an actuator engaging both of said blades and adapted to move both blades simultaneously out of normal position while maintaining them separated; a detent; thermal means carried by the one blade and adapted to engage the detent to retain said one blade in actuated position, said means being adapted also to release the said one blade at a predetermined temperature; and means on the second blade 20 for engaging the retained blade when the actuator is released. 25

19. A circuit breaker comprising two flexible contact blades normally biased to circuit open position; a detent formed integrally with one of said blades; a thermally responsive ratchet 30 carried by the second blade and adapted to engage the detent to retain said second blade in an actuated position below a predetermined temperature; and an actuator adapted to engage both of said blades and to move both blades 35 simultaneously while holding them separated, the said one blade being adapted to engage the retained second blade only when the actuator is released after being operated.

20. A circuit breaker comprising two flexible 40 contact arms normally biased to circuit open position; an actuator engaging said arms and adapted to move both simultaneously out of normal position while maintaining them separated, and thermal means on one of said arms adapted 45 to engage a portion of the other arm to provide for engagement of both of said arms when the actuator is released.
